UNITED STATES PATENT OFFICE.

WILLIAM F. BROCKWAY, OF ADEL, IOWA.

DESIGN FOR A CAMPAIGN-BADGE.

SPECIFICATION forming part of Design No. 26,191, dated October 20, 1896.

Application filed July 27, 1896. Serial No. 600,714. Term of patent 31 years.

To all whom it may concern:

Be it known that I, WILLIAM F. BROCKWAY, a citizen of the United States of America, residing at Adel, in the county of Dallas and State of Iowa, have invented and produced a new and original Design for Campaign-Badges, of which the following is a specification.

In the accompanying drawing the complete badge is shown in perspective.

It is the object of this design to produce an ornamental frame for the reception of the portraits of presidential candidates and the like, and to this end I have adopted the well-known mascot, a rabbit's hind foot, and by treating it somewhat conventionally, making it broad and flat and arranging it artistically about the two blank flat spaces that are to receive

the portraits, it forms a frame for the two portraits.

The reference-letter A is used to indicate the foot, and A² the toes. The flat surfaces are indicated by the reference-letters B B.

What I claim as my invention is—

The design for a campaign-badge, comprising a picture-frame bearing the representation of a rabbit's rear foot broadened and flattened and arranged to form a frame or background and two flat spaces at the central portion of the frame designed for the reception of portraits, substantially as set forth.

WILLIAM F. BROCKWAY.
